UNITED STATES PATENT OFFICE.

GUSTAVOS HEIDEL, OF ST. LOUIS, MISSOURI, ASSIGNOR TO THE GLOBE ELECTRIC COMPANY, OF SAME PLACE.

ELECTRIC-ARC LAMP.

SPECIFICATION forming part of Letters Patent No. 638,512, dated December 5, 1899.

Application filed March 8, 1899. Serial No. 708,222. (No model.)

To all whom it may concern:

Be it known that I, GUSTAVOS HEIDEL, a citizen of the United States, residing at the city of St. Louis, in the State of Missouri, have invented certain new and useful Improvements 5 in Electric-Arc Lamps, of which the following is a full, clear, and exact description, reference being had to the accompanying drawings, forming part of this specification.

10 My invention relates to an electric-arc lamp in which the carbon pencils are maintained in contact with each other by a simple arrangement comprising a pair of coincident spring-controlled sheaves by which the stem of the 15 lower-carbon holder connected thereto is gradually raised as the pencils are worn away or consumed.

Figure I is a vertical sectional view taken through the lamp. Fig. II is a cross-sectional 20 view of the spring-sheaves. Fig. III is a top view of the sheaves. Fig. IV is a view of the lower-pencil holder, with its supporting-stem shown in cross-section. Fig. V is a view of 25 a modified construction, illustrating the lamp applied to a supporting-standard, so as to serve as a student's lamp. Fig. VI is a view showing the lamp illustrated in Fig. V applied to a gas-bracket.

1 designates the lamp-housing, provided 30 with a dome top 2, having an eye 3, by which the lamp may be suspended. Carried by the housing 1 at its lower end is an upper ring 4, to which a lower ring 5 is connected by a hinge 6, so that the said rings may be separated by 35 swinging the lower one on said hinge, and when brought together the rings are connected by a suitable catch 7.

8 designates a globe attached to the lower ring by means of screws 9. 40 Seated in the ring 4 is a cross-bar 10, that is provided with a central aperture, in which a sleeve 11, that supports the upper-pencil holder, is held.

13 are the pencils in the upper holder.

45 Within the sleeve 11 is a bushing 14, of insulating material.

15 designates a stem, by which the lower-pencil holder 16 is carried, this lower holder being provided with pencils 17. The stem 50 extends through the bushing 14, and its up-

per end is attached to and supported by a cross-piece 18, that is movably mounted in the housing 1 and connected to lift-cords 19.

In the housing 1 are supports 20, that contain a shaft 21, and on this shaft are grooved 55 sheaves 22 and 23, to which the lift-cords 19 are connected. The sheaves 22 and 23 are both loosely mounted on the shaft 21, (see Fig. II,) and one end of one of the cords 19 is connected to one of these sheaves, while 60 one end of the other cord 19 is connected to the other sheave. Interior of the sheaves is a convoluted spring 24, having one end thereof attached to one of the sheaves and the other end attached to the other sheave. It 65 will therefore be understood that when the cords 19 are drawn upon the convolutions of said spring are drawn together, tightening or winding the spring, and when the cords are relieved the spring tends to unwind and turn 70 one of the sheaves in one direction and the other in the opposite direction and wraps the cords around the peripheries of the sheaves. Therefore when the pencils 13 and 17 are to be introduced into their holders the lower 75 holder is drawn down into the position shown in dotted lines, Fig. I, and the spring 24 is thereby wound within the sheaves, after which on relieving the downward pull upon said holder and its supporting-stem 15 the 80 lower holder again moves upward into the position shown in full lines, Fig. I, to bring the pencils into contact with each other, and as the pencils wear away they are kept together by the gradual ascension of the lower 85 pencils.

25 designates a binding-post, to which one of the supply-wires 26 is connected, and 27 is a wire connecting the binding-post 25 to a binding-post 28, carried by the cross-piece 18, 90 from which the current is conducted through the stem 15 to the pencils 17.

29 designates a binding-post having a supply-wire 30 connected thereto. Leading from the binding-post 29 is a wire 31, that connects 95 with a contact 32, carried by the upper ring 4.

33 is a contact carried by the lower ring 5 and arranged to bear against the contact 32 when the rings 4 and 5 are placed together.

34 is a binding-post carried by the sleeve 100

11 of the upper-pencil holder, this last-named binding-post being connected to the contact 33 by a wire 35.

It will be apparent from the foregoing that 5 when the lamp is closed by raising the lower ring 5 against the upper ring and connecting it thereto by the catch 7 the contacts 32 and 33 are brought together and a circuit is completed from the binding-post 29 to the 10 pencil-holder 12, but as soon as the lower ring 5 is moved away from the upper ring the contacts 32 and 33 are separated and the circuit to the pencil-holders is broken, thereby removing all danger in the handling of the 15 carbon-holders and replacing the pencils therein.

In Fig. V, I have shown the lamp in the form of a student's lamp, in which the housing 1^a is supported on a standard 36. The interior 20 of the lamp is approximately the same as that shown in Fig. I; but the stem 15^a extends exterior of the lamp and is curved outwardly and upwardly to receive the lower pencil 17^a, that is encircled by a sectional disk 37, adapted 25 to receive the dust resulting from the consumption of the carbon. The upper pencils 13^a are supported in a holder 12^a, secured to and projecting from the sleeve 11^a. The pencils are inclosed by a suitable chimney 8^a. The conducting-wires are controlled by a cut-out 37.

In Fig. VI, I have shown the lamp illustrated in Fig. V attached to a gas-bracket A by means of a support 36^a.

35 I claim as my invention—

1. In an electric-arc lamp, an upper-pencil

holder, a lower-pencil holder, a stem on which said lower-pencil holder is supported, a pair of sheaves, a convolute spring coiled within said sheaves and having its ends connected 40 to them respectively, and a pair of cords each of which has connection with said stem, and one of which is connected to one of said sheaves and the other to the other of said sheaves; substantially as described. 45

2. In an electric-arc lamp, a pair of pencil-holders, one of which is movable with relation to the other, a housing, a pair of sheaves mounted in said housing and having within them a convolute spring the ends of which 50 are connected to them respectively, means of connection from said movable pencil-holder to said sheaves, a ring carried by said housing, a second ring hinged to said first-named ring, contacts carried by said rings adapted 55 to bear against each other when the rings are brought together, and means for supplying electrical current to said parts; substantially as described.

3. In combination with the movable pencil 60 of an arc electric light, oppositely-rotating coaxial sheaves having winding connections with the opposite sides of the pencil, and a convolute spring coiled within said sheaves and having its ends attached to them respectively, whereby they are wound in opposite directions; substantially as described.

GUSTAVOS HEIDEL.

In presence of—

E. S. KNIGHT,
G. A. TAUBERSCHMIDT.
